ELECTRICAL HEATING DEVICE

William Wesley Hicks, San Francisco, Calif., assignor to Wesix National Company, San Francisco, Calif., a corporation of Delaware

Application July 2, 1928. Serial No. 289,709

2 Claims. (Cl. 219—46)

This invention relates generally to devices for converting electrical energy into heat.

It is an object of this invention to devise a novel unit or electrical heating element which can be universally applied to supply heat either by conduction or convection.

It is a further object of this invention to devise an electrical heating unit which is inherently flexible and which can be looped upon itself or which can be bent to various forms without permanent deformation.

It is a further object of this invention to devise a heating unit having a relatively small heat lag and a relatively efficient heat transmitting surface.

Further objects of the invention will appear from the following description in which I have set forth the preferred embodiment of my invention. It is to be understood that the appended claims are to be accorded a range of equivalents consistent with the state of the prior art.

Referring to the drawing:

Figure 1 is a side elevational view of a device incorporating my invention.

Fig. 2 is an enlarged cross sectional detail of a portion of the unit shown in Fig. 1.

Fig. 3 is a detail perspective view showing the metal strip employed for forming my flexible metal sheath.

Fig. 4 is a front elevational view of an electrical air heater incorporating a unit such as shown in Fig. 1.

Fig. 5 is a cross sectional view taken along the line 5—5 of Fig. 4.

Fig. 6 is a front elevational view showing another manner in which device of Fig. 1 can be looped about supporting means.

Fig. 7 is a detail of a modified form of the unit in which a single sheath encloses a pair of resistance conductors.

Fig. 8 is a cross sectional view taken along the line 8—8 of Fig. 7.

In the past it has been common practice to enclose insulated resistance conductors within an elongated metal tube. In adapting such heating units to various conditions of operation or to different heating appliances with which they are employed, they can be bent from the normal shape in which they are manufactured, but such bending effects a permanent deformation. In other words a small amount of bending of the metal sheath or tube exceeds the elastic limit of the metal with the result that the bend is permanent. It is apparent that bending of an element of this kind must not only be done carefully

so as not to injure the element, but in most cases the elements cannot again be straightened or bent to a different shape to suit other conditions. Furthermore this bending cannot be accomplished quickly and readily as with the invention herein disclosed.

In my invention I enclose an insulated resistance conductor in a metal sheath but this sheath is constructed in such a manner as to be inherently flexible to such a degree that the elements can be looped upon itself without permanent deformation.

Referring to the drawing for a detailed description of the preferred embodiments of my invention, in Figs. 1 and 2 I have shown an electrical heating unit comprising a flexible resistance conductor 11 which is preferably convoluted so as to provide sufficient resistance and a high degree of flexibility. Conductor 11 is provided with flexible insulation, which in this case is preferably formed by a plurality of contiguous tubes or beads 12 of insulating material. The conductor and the bead or tubes are enclosed within an inherently flexible metal case 13.

As an example of an inherently flexible sheath, I have shown a construction utilizing a strip 14 made of metal having relatively high resilience. This strip is formed as shown in Fig. 3 so as to provide oppositely extending edges 16 and 17 and is wound in the form of a helicoid or a spiral in such a manner that the projecting edges 16 and 17 are caused to interlock between adjacent convolutions. This interlocking relationship is clearly shown in Fig. 2. An elongated sheath formed in this way is extremely flexible. It can be bent to a comparatively small radius and can be rebent a number of times without injury. In looping such a sheath upon itself the elastic limit of the metal is not exceeded and therefore the sheath does not take a permanent deformation. Another advantage of a sheath of this kind is that it is of comparatively light weight compared to a solid tube of equal lateral strength, and therefore my unit has small heat lag.

The insulating tubes 12 are preferably of such a length, and have sufficient clearance between the sheath 13 that they will not be cramped and broken when the sheath is flexed to its minimum radius. For connection with the ends of conductor 11, I have shown suitable connection blocks 18 mounted upon the ends of the flexible sheath 13. As a means for securing these blocks to the sheath, I have shown each block provided with a portion 19 adapted to project within the cooperating end of sheath 13. A suitable clamp 110

21 surrounding the end portion of sheath 13, serves to effectively clamp the sheath to portion 19. A suitable connection terminal 22 is provided upon block 18, and a lead from conductor 11 extends to terminal 22 thru the opening 23.

5 In Figs. 4 and 5 I have shown one particular use for the units shown in Figs. 1 and 2. In this case the unit forms an electrical heating element for an air heater. This heater has been shown conventionally as comprising an outer housing 26 having an open front which is covered by a suitable grille or front plate 27. Positioned within the housing 26 there is a shell 28 which accommodates a supporting plate 29. A flexible unit such 10 as that described above and which has been indicated generally at 31, is looped about the support 29 in any convenient way. When in use convection currents can flow thru grille 29 into and out of the open front shell 28, and likewise into 15 the lower and out of the upper portion of housing 26 between the shell 28 and the housing.

It is to be noted that because of the character 20 of my flexible metallic sheath, the outer surface of this sheath is grooved and thus provides an effective augmented heat transmitting surface. Such a grooved surface is of particular advantage 25 when my unit is employed for heating fluids such as air, as it materially increases the radiating surface and increases the surface of contact between 30 the sheath and surrounding fluid medium.

In Fig. 6 another adaptation of my heating unit 35 is shown, in which this unit 31 is looped about and supported by a plurality of insulating knobs 32. While in case of the uses illustrated in Figs. 4, 5 and 6, the unit effects heating principally by radiation and convection, it is apparent that it can 40 also be employed for heating by direct conduction, as for example the unit can be wrapped about or otherwise placed in heat conducting relationship with a body to be heated.

In Fig. 7 I have shown a flexible sheath 33 similar in construction to that shown in Figs. 1 and 2, but adapted to enclose a plurality of resistance conductors 11. In this case the sheath 33 is flattened and encloses two conductors 11 and their insulating tubes in side by side relationship. The properties of a unit constructed in this manner are similar to the properties of the single conductor unit previously described.

80 I claim:

1. In an electrical heating device, a flexible resistance conductor, a plurality of insulating tubes strung upon the conductor, a second conductor having insulating tubes strung upon it, said first and second conductor being arranged 85 with the respective insulating tubes contiguous, and an elongated flexible metal sheath surrounding said insulated conductor and retaining them contiguously to form a heating device which may be looped to assume different positions without 90 assuming a permanent set.

2. In an electrical heating device, an elongated helical resistance conductor, a plurality of refractory insulating tubes strung upon said conductor, and an elongated metal sheath enclosing 95 said tubes and said conductor, said sheath comprising a spirally wound strip of metal having interlocking turns, whereby said sheath is capable of assuming various curved contours without 100 permanent deformation, the insulating material 105 of which said tubes are composed being relatively compact, and having relatively small heat lag, thereby affording efficient heat transfer from said conductor to said flexible sheath in any position 110 which the sheath may assume, each of said tubes being of a length at least equal to but less than twice the width of said strip.
